UNITED STATES PATENT OFFICE.

JEAN BAPTISTE GUSTAVE ADOLPHE CANET, OF PARIS, FRANCE, ASSIGNOR
OF ONE-HALF TO THE SIR JOSEPH WHITWORTH & COMPANY, LIMITED,
OF OPENSHAW, MANCHESTER, ENGLAND.

BREECH MECHANISM FOR ORDNANCE.

SPECIFICATION forming part of Letters Patent No. 502,172, dated July 25, 1893.

Application filed December 6, 1892. Serial No. 454,278. (No model.)

To all whom it may concern:

Be it known that I, JEAN BAPTISTE GUSTAVE ADOLPHE CANET, engineer, a citizen of the Republic of France, and a resident of

5 Paris, France, have invented certain new and useful Improvements in Breech Mechanism for Ordnance; of which the following is a specification, reference being had to the accompanying drawings.

10 My invention relates to breech mechanism and is designed to provide mechanism for facilitating the opening and closing of the breech of heavy guns.

The said invention consists in various combinations of parts adapted to produce successively all of the movements necessary for the opening or the closing of the breech of a gun by the continuous movement of a lever or handle in one or the other direction.

15 The said invention is illustrated in the accompanying drawings, in which—

Figure 1 is a rear end view of a gun provided with my improved breech-mechanism. Fig. 2 is a similar view showing portions of the mechanism in transverse section. Fig. 3 is a 20 longitudinal central section. Fig. 4 is a horizontal section taken on two different planes the right half being taken on the line x, x Fig. 1, and the left half being taken on the line y, y , Fig. 1. Fig. 5 is a sectional plan 25 taken on the line z, z Fig. 1.

Like letters indicate the same parts throughout the drawings.

A is a portion of the body of the gun.

30 B is the breech-plug or screw.

C is a metal end plate or bracket attached to the breech end of the gun and properly constructed for supporting the breech-mechanism. D is the carrier-ring hinged to the said 35 end plate at the side of the breech in the usual manner.

D' is a bracket formed with and projecting rearwardly from the carrier ring and serving to support the breech-plug when the same is 40 withdrawn from the breech. It also carries the withdrawing mechanism. B² is the ordinary catch or locking bolt for locking in a well known manner the said carrier-ring to the end plate when the breech plug is in place, 45 and also for locking the said carrier-ring and

breech screw together as soon as the latter is out of the breech. In Fig. 4 this catch bolt is shown in the position wherein it locks the carrier ring to the end plate C of the gun.

E is a shaft provided with a hand-lever E' 55 for operating the breech mechanism. E' Fig. 5 is an endless screw or worm keyed on the said shaft. F' is a worm wheel fitted to turn freely on the vertical shaft F and driven by the said worm. The shaft F forms the pivot 60 on which the carrier ring is turned to and away from the breech. F² is a pinion with helical teeth cast or otherwise formed solidly or in one piece with the said worm wheel.

G is a pinion with helical teeth geared with 65 the pinion F².

H is an endless screw with multiple threads geared with the pinion G and having its axis parallel to that of the said pinion. This endless screw is supported at its ends in suitable 70 bearings in the carrier bracket D' as clearly shown at D² D² Fig. 3.

B' is a toothed sector with inclined teeth formed or fixed on the breech-screw B and geared with the endless screw H. The teeth 75 of the gear wheels F², G, and of the endless screw and sector are inclined at an angle of forty-five (45) degrees. The axes of the pinion wheels and screws are arranged to bear on steel or other hard metal dies to minimize 80 the friction.

With my improved mechanism the continuous turning of the actuating handle E' in one direction first releases the breech-plug from the screw threads of the gun, secondly withdraws the said breech-plug from the breech 85 on to the carrier bracket, and thirdly turns the same about the pivot of the carrier away from the breech; and the continuous turning of the said handle in the opposite direction 90 closes the breech; that is to say:—In opening the breech the handle E' being turned in the proper direction, first acts through the shaft E the worm E', the helical pinions F² and G, the endless screw H, and sector B', to turn 95 the breech screw B about its axis to release the threads of the same from those in the gun. Then without interruption of the movement of the lever handle and shaft E the turning of the breech-plug about its axis is 100

arrested by a stop *b* arranged to limit its rotation, but the screw or worm *H* continuing to turn about its axis and being prevented from moving endwise, its teeth act like screw-threads on those of the sector *B'*, that is to say, the said endless screw and sector act as a screw and nut and thereby the breech plug *B* is drawn out of the breech. Then the breech plug having been drawn back till it abuts 5 against the rear end of the carrier bracket *D'* and into a position which permits the locking bolt *B²* to retire from engagement with the plate *C* the carrier ring and bracket are free to turn upon the hinge or pivot at the side of 10 the breech. As at this moment the rotation of the endless screw *H* is stopped by reason of the abutment of the breech-plug against the bracket *D'* and the said screw becomes so to speak solid with the bracket, the continued 15 rotation of the handle acting through the helicoidal gearing to thrust the endless screw *H* backward causes the carrier and the breech-screw to turn about the shaft *F* away from the breech. The closing of the breech is effected by turning the handle in the opposite 20 direction, that is to say, by continuously turning the said handle in the proper direction to reproduce the above described movements in 25 the reverse order.

30 What I claim is—

1. In a breech-loading gun, the combination

with the breech-screw, of the toothed sector *B'*, the endless screw or worm *H* having its axis parallel with that of the gun, and gearing with the sector *B'*, a crank-shaft *E*, and 35 the helical wheels *F²*, *G*, worm wheel *F'*, and worm *E²*, for gearing the worm *H* with the said operating crank shaft, substantially as and for the purpose specified.

2. The combination of the breech-screw, the 40 carrier-ring hinged or pivoted to one side of the breech and through which the breech-screw can slide, the bracket *D'* on the carrier-ring for supporting the breech-screw when the latter is withdrawn from the breech, the 45 toothed sector *B'*, the endless screw or worm *H*, gearing with the said sector *B'*, and supported in bearings in the bracket *D'* with its axis parallel to that of the gun, the crank shaft *E*, geared with the worm *H*, through a 50 worm wheel *F'*, and helical wheels *F²*, *G*, the end of the bracket *D'* being constructed to form a stop to limit the sliding movement of the breech-screw, substantially as described for the purpose specified.

In witness whereof I have hereunto set my hand this 10th day of November, 1892.

JEAN BAPTISTE GUSTAVE ADOLPHE CANET.
